Primary Examiner—Celia A. Murphy(74) *Attorney, Agent, or Firm*—Jeffer, Mangels, Butler & Marmaro, LLP(57) **CLAIM**

The ornamental design for a shoe bottom, as shown and described.

DESCRIPTION

FIG. 1 is a bottom plan view of a shoe bottom showing our new design;

FIG. 2 is a left side elevational view thereof; and,
 FIG. 3 is a right side elevational view thereof.

The broken lines in FIGS. 2 and 3 are for illustrative purposes only and form no part of the claimed design.

The broken lines in the toe portion of the in Figures define the boundary of the design. The broken boundary lines form no part of the claim.
